SUMMARY BOARD

George H. Dawson, Chicago, Paul O. Unger, Glen Ellyn, and Fred D. Wedge, Lombard, Ill., assignors to Wilson-Jones Company, Chicago, Ill., a corporation of Massachusetts

Application March 14, 1935, Serial No. 10,976

17 Claims. (Cl. 120—33)

This invention relates to a summary board whereby a plurality of sheets may be supported in horizontal overlapping relationship so that single columns on each of the sheets may be held in juxtaposed positions to facilitate summarization of the data contained in the exposed columns.

It is an object of our invention to provide improved means for removably holding a plurality of banks of sheets in overlapped relationship so that data may be read from the exposed columns of each bank of sheets along a horizontal line. It is a further object of our invention to provide improved means for adjusting the angularity of the line guide. It is a further object of our invention to provide means for facilitating the impalement of sheets on the aligning pins when the sheet retaining bar is not associated with the board. It is a further object of our invention to provide a non-metallic line guide resistant to warping. Other objects of our invention will become apparent upon reading the following description, taken in conjunction with the accompanying drawings, in which

Figure 1 is a fragmentary perspective view of a summary board embodying the invention;

Figure 2 is a top plan view of the summary board with portions broken away to facilitate illustration of the structure;

Figure 3 is a cross section taken along the line III—III of Figure 2;

Figure 4 is a cross section taken along the line IV—IV of Figure 2;

Figure 5 is a cross section of the sheet retaining bar in open position;

Figure 6 is a fragmentary perspective view of a modified form of sheet retaining bar;

Figure 7 is a fragmentary perspective view of the modified embodiment of Figure 6 in open position;

Figure 8 is a perspective view of a summary board and bar in disassociated relationship;

Figure 9 is a cross sectional view showing the novel shape of the line guide;

Figure 10 is a detail perspective view showing the means of securing one end of the sheet retaining bar to the plate member;

Figure 11 is a detail view showing the rear side of the securing means shown in Figure 10;

Figure 12 is a plan view of one form of line guide adjusting mechanism, with parts broken away to facilitate illustration of the structure;

Figure 13 is a cross section taken along the line XIII—XIII of Figure 12;

Figure 14 is a cross section taken along the line XIV—XIV of Figure 12;

Figure 15 is a view similar to Figure 12, showing another form of mechanism for regulating the travel of the line guide; and

Figure 16 is a cross section taken along the line XVI—XVI of Figure 15.

In the drawings, the reference numeral 2 indicates a plate member which is preferably flat, and which may be supported at any desired inclination by means of an easel structure, indicated at 3, Figure 8. The preferred easel structure does not constitute part of this invention and is fully described in United States Letters Patent No. 1,883,255 granted October 18, 1932 to Paul O. Unger. The plate member 2 is provided at its edges with downward walls 4 to impart rigidity and strength to the plate member. The walls 4 also cooperate with the plate member to form a space large enough to receive the easel structure in collapsed condition.

A metal strip 5 and a spacing strip 6 are secured to the top wall 4 in any suitable manner such as welding or riveting. The spacing strip 6 is of less height than the strip 5 so that a recess is formed between the wall 4 and the strip 5 with the strip 6 serving as a base for the recess. The recess is traversed, near one end, by a pin 7, and at a centrally located point by a similar pin 8.

A sliding latch member 9 is secured to the rear surface of the strip 5 adjacent the end opposite the pin 7 by means of a pair of studs 10. The member 9 is provided with a pair of elongated apertures 11 through which the studs 10 pass. The latch member 9 is provided with a turned over lip 12 which projects beyond the front surface of the strip 5. The slots 11 are long enough to permit the latch member 9 to be moved laterally a distance sufficient to move the lip 12 past the edge of the strip 5. The latch 9 is provided with a finger piece 13 to facilitate sliding the latch.

A sheet retaining bar 14 is adapted to be secured adjacent the upper edge of the plate member 2. The sheet retaining bar comprises two metal strips 15 and 16 which are hinged at their meeting edges, as indicated at 17. The strip 15 is provided with a downturned flange 18 which is adapted to fit in the recess between the top wall 4 and the strip 5. One end of the flange 18 is provided with a notch 19 adapted to fit around the pin 7. The flange 18 is provided with another notch 20 adapted to fit around the pin 8. The end 45 of the strip 15 opposite the notch 19 is slotted, as indicated at 21, to provide clearance for the lip 12.

The strip 16 is provided with a downturned flange 22 similar to the flange 18 except that the positions of the notch 19 and the slot 21 are re-

5

55

versed. Accordingly, the sheet retaining bar may be positioned with either flange 18 or 22 in the recess between the top wall 4 and the strip 5. The latch 9 must be moved outwardly to the position 5 shown in Figure 8 to allow either flange 18 or 22 to be inserted in or removed from the recess. A simple inward sliding movement of the latch 9 causes the lip 12 to move into the slot 21 to provide adequate protection against accidental separation of the sheet retaining bar from the upper edge of the plate member. The opposite end of the flange is held securely against relative vertical movement by the pin 7 fitting into the notch 19. Lateral movement of the sheet retaining bar is 10 prevented by the pin 8 fitting into the notch 20.

A series of sheet aligning pins 23 is provided on each of the strips 15 and 16. These pins 23 are equally spaced along the strips and are arranged in pairs so that sheets impaled on one 15 series of pins may be turned over and impaled on the other series without any lateral movement. The strip 15 is provided with another series of sheet aligning pins 24 spaced intermediately of the pins 23. Each of the series of pins 24 is recessed at its free end, as indicated at 25, to receive the free end of an arched prong member 26. Each of the arched prong members 26 has one end rigidly secured to the strip 16 in any suitable manner.

30 The latch 9 and associated structure holds one of the flanges 18 or 20 rigidly adjacent the top edge of the plate 2. The other of the flanges 18 or 20 and its strip 15 or 16 is free to move on the hinge 17 to separate the end of the arched prong members from the ends of the pins 24. The engagement of the arched prongs 26 and the pins 24 prevents relative movement of the strips 15 and 16 in one direction beyond the point where the strips 15 and 16 are in substantially the same plane. Movement of the strips 15 and 16 beyond a predetermined point in the opposite direction is prevented by means of a pair of metal strips 27 and 28 welded to the under side of the strips 15 and 16, respectively, and arranged so that their ends abut each other when the strips have been moved a predetermined distance. Although a single pair of strips 27 and 28 is sufficient for the purpose described, we prefer to use a plurality of pairs of each strip.

50 When the sheet retaining bar is open a plurality of sheets may be impaled on the pins mounted on the strip 15, or on the arched prongs and pins secured to the strip 16. The strip 27 may be provided with a depending portion or foot 29 parallel with the flange 18 and spaced therefrom so that the strip 5 is adapted to fit between the flange 18 and the portion 29. Preferably the depending portion 29 projects below the flange 18 so that when the bar 14 is separated from the plate 2 and 55 is placed on a flat surface in open position, the aligning pins 23 and 24 on the strip 15 project vertically to facilitate the impalement of sheets thereon. When the bar is closed the impaled sheets may be moved from the pins on one strip 60 15 or 16 to the pins on the other. The arched prongs 26 serve as guide means as well as retaining means for the sheets.

The sheet retaining bar is provided with spring means to hold the strips 15 and 16 in either 65 closed or open position. In the preferred embodiment (Figure 4), each of the strips 15 and 16 has a portion of its inner edge adjacent the hinge 17 curled back to form a lip 30. A C-shaped compression spring 31 has its ends 32 70 curled to engage the lips 30. As shown in Fig-

ure 4, the line between the points of application of force, that is the line between the points of engagement of the ends 32 of the spring with the lips 30, is above the center of the hinge 17. Accordingly, the force of the spring 31 acts to hold the strips 15 and 16 closed. When the sheet retaining bar is open, the line between the points of application of force lies below the center of the hinge 17 so that the force of the spring 31 acts to hold the strips 15 and 16 open. The number 10 of springs used may vary with the length of the bar 14.

In the modified embodiment of the summary bar illustrated in Figures 6 and 7, the only structural difference from the preferred embodiment 15 is in the specific form of spring utilized for holding the strips 15' and 16' in either closed or open position. In this embodiment the strips 15' and 16' are provided with registering recesses 33 and a curled lip 34 at the extremity of each recess. A 20 tension spring 35 positioned in each pair of recesses 33 has its opposite ends secured to the lips 34. When the strips 15' and 16' are in closed position, the springs 35 exert force to hold them closed, and when the strips 15' and 16' are 25 in open position the springs 35 exert force to hold them open. Figures 6 and 7 do not show the bar equipped with the extensions 29, but it will be understood that either embodiment of the sheet retaining bar may be built with or without the extensions.

A metal strip 37, having outturned flanges 38, is rigidly secured to one side 4 in any suitable manner. The length of the strip 37 exceeds the length of the side wall 4 by a distance sufficient to cause the top flange 38 to lie substantially flush with the free flange of the sheet retaining bar 14 when one of the flanges 18 or 22 is secured adjacent the top of the plate member 2. In the preferred embodiment of the invention a rod 39 of 40 circular cross section is secured between the flanges 38 by means of screws 40. The rod 39 is serrated to form a series of teeth 41 extending along the entire length of the rod 39. The teeth 41 are preferably positioned on the side of the 45 rod 39 away from the strip 37. The rod 39 is fixed with respect to the flanges 38 so that the serrated portion of the rod remains on the side away from the strip 37.

A housing 42 is mounted on the rod 39 and 50 is adapted to be moved along the rod by means of mechanism hereinafter described. The housing 42 comprises a top wall 43, and side walls 44, 45, 46 and 47. A metal strip 48, permanently secured to the side wall 44, has one end 49 projecting over the plate member 2 in a plane substantially parallel thereto. A line guide 50, made of 55 wood or other light, rigid material is permanently secured to the strip 48 by means of rivets 51 or in any other suitable manner.

As shown in Figure 9, the line guide 50 is 60 grooved out, as indicated at 52, to reduce the cross sectional area of the line guide along its center portion so that the top and bottom surfaces of the line guide approach parallelism. The grooving out of the underside of the line 65 guide apparently tends to equalize the forces set up in the line guide by atmospheric conditions and thereby reduces the possibility of warpage. The edges of the line guide are beveled, as indicated at 53, to facilitate reading of the data 70 contained on the sheets 54 mounted on the sheet retaining bar. Accordingly it is important that the bar 51 should be prevented from warping. The line guide may be made of metal, but wood 75

is preferred because of its lightness and inexpensiveness.

The mechanism associated with the housing 42 for moving the housing along the rod 39 includes a pair of rollers 55 and 56 provided with teeth 57 and 57' adapted to mesh with the teeth 41. The rollers 55 and 56 are mounted in a channel member 58 by means of shafts 60 and 59, respectively. A pair of compression springs 61 urge the channel member 58 towards the rod 39 and maintain the teeth 57 and 57' constantly in mesh with the teeth 41. The shaft 60 projects through an aperture 62 in the top wall 43 and is provided with a knurled knob 63 fixed to its upper end. Rotation of the knurled knob 63 rotates the roller 55 and causes the housing 42 to move along the rod 39. The housing may be pushed up or down the rod if the knob 63 is left free to rotate.

20 The housing 42 contains a second pair of rollers 64 and 65 engaging the periphery of the rod opposite the serrated portion 41. The rolls 64 and 65 are mounted in a channel member 66 by means of shafts 67 and 68 respectively. The shaft 67 is fixed to the top wall 43 to fix the roller 64 with respect to the housing 42. The shaft 68 is free of any direct connection with the housing so that the channel member 66 may be moved within the housing, about the shaft 67 30 as a pivot, to adjust the angularity of the line guide with respect to the plate 2.

The means for moving the channel member 66 includes a threaded stud 69 rigidly secured thereto and having a knurled disc 70 threaded on the stud between the channel member 66 and the side wall 44. The top wall 43 is provided with an aperture 71 through which the periphery of the disc 70 is adapted to extend. The side wall 44 and the strip 48 are apertured to allow the stud 40 69 to pass therethrough.

If it is desired to raise the free end of the line guide 50 with respect to the end secured to the metal strip 48, the disc 70 is rotated in a direction to move the stud 69 to the right as viewed 45 in Figures 12 and 14. Since the disc 70 is prevented from moving by the edges of the aperture 71, and the upper end of the channel 66 is prevented from moving by the shaft 67, the lower end of the channel will be moved toward the right 50 around the shaft 67 as a pivot. The apertures 72 and 73 in the walls 46 and 47, through which the rod 39 passes, are sufficiently large to permit the slight lateral movement necessary to allow the housing to tilt and change the angle of the line guide 50 with respect to the plate 2. If the free end of the line guide is to be lowered with 55 respect to the fixed end, it is necessary to rotate the disc 70 in the opposite direction.

In the embodiment of the invention illustrated 60 in Figures 15 and 16 a square rod 74 has been substituted for the circular rod 39. It will be understood that the rod 74 may be of any non-circular cross section. The ends of the rod 74 are swiveled in the flanges 38, as indicated at 65 75, so that when the line guide 50 is lifted from the plate 2 the rod 74 pivots with the housing 42'.

The driving roller 76 is preferably provided with a friction surface 77 which may be formed 70 of rubber or any other suitable material. Although the friction surface 77 is shown as being provided with projections 78, the surface may be comparatively smooth. The roller 76 and another roller 79 having a smooth surface are 75 mounted in the housing 42' in the same manner

as the rollers 55 and 56 are mounted in the housing 42.

The housing 42' contains a channel member 66' similar to the channel 66 except that it is reversed. Rollers 80 and 81 are mounted in the same manner as rollers 64 and 65 and serve the same purpose. The only difference is that the rollers are provided with flat peripheries to make better contact with the flat surface of the rod 74. The means for adjusting the angularity of the line guide is the same as described in connection with Figures 12, 13 and 14.

Although we have described several embodiments of our invention in considerable detail, it will be understood that the description thereof is illustrative, rather than restrictive, as many details may be modified or changed without departing from the spirit or scope of our invention. Accordingly, we do not desire to be restricted to the exact construction described, except as limited by the appended claims.

We claim:

1. In a summary board, a plate member, one edge of said plate member being provided with a flange, a metal strip secured in spaced relationship to said flange, and a sheet retaining bar provided with a flange insertable in the space between said first mentioned flange and said metal strip.

2. In a summary board, a plate member, one edge of said plate member being provided with a flange, a metal strip secured in spaced relationship to said flange, a plurality of pins traversing the space between said flange and said strip, and a sheet retaining bar provided with a flange notched to engage said pins, and a latch engageable with said bar to retain said second mentioned flange in said space.

3. In a summary board, a plate member, a metal strip secured in spaced relationship to one edge of said plate member, a sheet retaining bar having a flange at one edge adapted to be retained in the space between said plate and said strip, and a plurality of feet secured to said bar and spaced from said flange to lie on the opposite side of said strip.

4. In a summary board, a plate member, a rod non-circular in cross section pivotally mounted adjacent one edge of said plate member, a housing mounted on said rod, a friction roller in said housing, means to maintain said friction roller against said rod, and means accessible from outside said housing to rotate said friction roller so as to move said housing along said rod.

5. In a summary board, a sheet retaining bar including a pair of metal strips hinged at their meeting edges, and a spring secured to both of said strips, said spring being adapted to hold said strips in either of two positions.

6. In a summary board, a sheet retaining bar including a pair of metal strips hinged at their meeting edges, a plurality of sheet aligning pins mounted on one of said strips, a plurality of curved sheet retaining prongs secured to the other strip, and a spring secured to said strips.

7. In a summary board, a sheet retaining bar including a pair of metal strips hinged at their meeting edges, a plurality of sheet aligning pins mounted on each of said strips, and a spring secured to said strips, the points of engagement of said spring with said strips being above the axis of the hinge when said strips are in one position, and below the axis of the hinge when said strips are in another position.

8. In a summary board, a sheet retaining bar

- comprising a pair of sections having complementary hinge sleeves on their inner edges, a hinge pintle inserted through said hinge sleeves, means on said sections to limit movement of said sections in each direction, and spring means to hold said sections in either extreme position.
9. In a summary board, a sheet retaining bar comprising a pair of hinged sections, a plurality of sheet aligning pins mounted on one of said sections, and a plurality of curved prong members mounted on said other section, said prong members being adapted to engage the ends of said aligning pins to retain a plurality of sheets on said bar.
- 10 15. 10. In a summary board, a plate member, a sheet retaining bar comprising a pair of hinged sections, one of said sections having a flange adapted to be positioned adjacent one edge of said plate member, and means for securing said flange adjacent said edge of said plate member.
11. In a summary board, a sheet retaining bar comprising a pair of hinged sections, a plurality of sheet aligning pins on one of said sections, a plurality of curved prong members on said other section, said prong members being adapted to engage the ends of said aligning pins when said sections are in closed position, and a plurality of feet secured to the underside of said first mentioned section, said feet being long enough to maintain said first mentioned section substantially parallel to any flat surface on which said bar may be placed when said sections are in open position.
12. In a summary board, a sheet retaining bar comprising two hinged sections, means to limit the angular movement of said sections, a lip projecting from each of said sections, and a spring secured against the underside of said bar by said lips, said spring acting to retain said sections in either of their extreme angular positions.
13. In a summary board, a plate member provided with a flange along one edge, a metal strip secured in spaced relationship to said flange, and a sheet retaining bar including a section having a flange adapted to be secured between said strip and said first mentioned flange, a plurality of sheet aligning pins on said section, a second section hinged to said first mentioned section for angular movement within predetermined limits with respect to said first mentioned section, and spring means adapted to hold said second section in either extreme position.
14. In a summary board, a plate member, a rod non-circular in cross section pivotally mounted adjacent one edge of said plate member, a housing mounted on said rod, and means carried by said housing cooperating with said rod to move said housing along said rod.
15. In a summary board, a plate member, a sheet retaining bar including a pair of metal strips hinged at their meeting edges, and means for securing said sheet retaining bar to one edge of said plate member with said hinge positioned beyond said plate member.
16. In a summary board, a plate member, a sheet retaining bar including a pair of metal strips hinged at their meeting edges, the outer edge of one of said strips having a flange adapted to be secured to said plate member, and a spring secured to both of said strips, said spring being adapted to hold said strips in either of two positions.
17. In a summary board, a plate member, a sheet retaining bar including a pair of metal strips hinged at their meeting edges, a plurality of sheet aligning pins mounted on one of said strips, a plurality of curved sheet retaining prongs secured to the other of said strips, the free ends of said curved prongs engaging the free ends of said aligning pins to form a plurality of closed arches, and cooperating means on one of said strips and one edge of said plate member to secure said sheet retaining bar to said plate member in such a manner as to allow said arches to be opened without removing said sheet retaining bar from said plate member.

GEORGE H. DAWSON.

PAUL O. UNGER.

FRED D. WEDGE.
